(57) **CLAIM**

The ornamental design for the linear actuator, as shown and described.

DESCRIPTION

FIG. 1 is a first side elevational view of the linear actuator; FIG. 2 is a second side elevational view of the linear actuator;

FIG. 3 is a top plan view of the of the linear actuator;

FIG. 4 is a bottom plan view of the of the linear actuator;

FIG. 5 is a first end view of the of the linear actuator; and

FIG. 6 is a second end view of the of the linear actuator; and,

FIG. 7 is a top perspective of the linear actuator.
